SEWELL DAVIS AND ALPHONSE LA FON, OF NEWARK, NEW JERSEY, ASSIGNEES TO
POLLY WIGGIN, INC., OF NEWARK, NEW JERSEY, A CORPORATION OF DELAWARE.

CAN OPENER.

Application filed September 23, 1925. Serial No. 58,080.

The invention relates to can openers, and aims to provide improvements therein.

The invention provides a can opener which may be held or supported manually and in which the physical effort of the user for operating it may be applied with a mechanical advantage and in a manner conducive to celerity of operation. The operation of the device is thereby easy and requires small exertion. The invention further provides a device which operates on a variety of sizes and shapes. It operates with facility on so-called round and square cans. The invention further provides a can opener of simple construction and capable of being made and sold at a moderate price.

An embodiment of the invention is illustrated in the accompanying drawing, wherein:

20 Figure 1 is a side elevation of said embodiment, the opener being shown in cutting relation with a can.

25 Fig. 2 is a view partly in side elevation and partly in section, and showing the opener in the position in which it is applied to the can.

Fig. 3 is a cross-section on the line III—III, Fig. 1.

Fig. 4 is a bottom plan, or underside, view.

30 Fig. 5 is a view showing the manner of holding and manipulating the opener in use.

Referring to said drawings, numeral 10 designates a cutter having a sharp edge 12 adapted to cut the can body just below the seam α where the top or end of the can is joined to the body, and 15 designates a feed and pressure roller (preferably roughened as indicated) adapted to bear on the flange at the back of the seam α and to draw the cutter 10 toward and to force it to cut through the can body (as shown in Fig. 1) and to be turned to propel or feed the opener around the edge of the can, the cutter 10 continuing its cutting as it is pulled around with the opener.

35 The cutter 10 is preferably circular and pivotally mounted on a pin 18, so as to turn as the opener is propelled around the edge of the can by the feed and pressure roller 15. An abutment 20, preferably in the form of a roller mounted on the pin 18, serves to limit the displacement of the opener, under the pressure of the pressure and feed roller 15, and thereby enables the said roller 15 to

bear with sufficient force against the inside 55 of the flange of the seam α to feed the opener as it is turned. The roller 20 is conveniently formed integrally with the cutter 10, and may serve to limit the penetration of the cutting edge 12 into the can body. 60

The cutter 10, and pin 18 on which it is mounted, are mounted on a handle or stock 22 adapted to be clasped or encircled by the fingers and thumb of one hand (see Fig. 5).

In order to provide for the separation of 65 the cutter 10 and pressure and feed roller 15 to permit the opener to be applied to the can, as shown in Fig. 2, the said roller 15 is conveniently mounted on a lever 25 pivoted to the said lever or stock 22, as indicated at 27. The lever 25 is adapted to be grasped in the hand at the same time as the lever or stock 22, the pressure or squeeze of the fingers on the outer end of the lever 25 drawing the opposite end carrying the 70 pressure and feed roller 15 toward the roller 20 and against the inside flange of the seam α , as shown in Fig. 1.

The pressure and feed roller 15 is preferably mounted directly on a shaft 30 journaled in the lever 25, and has at its end a crank 32 by which the shaft 30, and hence the roller 15, may be turned. A handle 33 serves as a ready means of grasping the crank. 85

The lever 25 and the crank 32 enable the roller 15 and cutter 10 to be brought together, and the roller 15 to be turned, with a mechanical advantage. These means also enable the bringing together of the roller 90 15 and cutter 10, and the turning of the roller 15 and consequently the propulsion or feed of the opener around the can, to be rapidly and readily performed.

In order to hold the underside of the pressure and feed roller out of contact with the surface of the can end, or a strengthening rib thereon, a stop 35 is conveniently provided on the stock 22 behind the roller 15. This stop may make contact with the can 100 end through an antifriction device, such as the ball 37 shown.

To protect the edge 12 of the cutter and also to protect users, the said cutting edge 105 may be surrounded with a guard 40.

For convenience and economy of manufacture, the stock 22 and lever 25 may be of sheet metal bent to U form. The lever 25

is conveniently fitted within the stock 22. The pin 18, carrying the cutter 10, is conveniently mounted on a bracket 42, which is formed separately from the stock 22 and 5 is fitted therein between the lever 25 and the stock. To fasten and hold the bracket 42, on the stock 22, the stock is conveniently provided with notches 44, into which a rib or projection 45 on the bracket, fits, and the 10 pin 27 on which the lever 25 is pivoted is passed through the bracket 42; the pin 27 and notch 44 and rib 45 act together to hold the bracket. A single pin 27 thereby serves to assemble the stock 22, lever 25 and bracket 15 et 42.

To use the opener, the feed and pressure roller 15 and cutter 10 are separated, and then placed over the flange formed by the seam α . The lever or stock 22 and lever 25 20 are then grasped in the hand and pressed together, bringing the roller 15 against the inner side of the flange of seam α and causing the cutter 10 to cut through the side of the can body just below the seam. The roller 15 is pressed against the flange with sufficient force to cause it to bite, and by turning the crank 32 with the other hand (Fig. 5), the opener as a whole is propelled around the can, the cutter 10 also turning 25 on its axis 18 and cutting the side of the can as the opener is propelled.

By resting or pressing the elbow of the hand which grasps the stock 22 against the side of the body, and with the forearm extending substantially straight out from the body, the arm is well braced, and enables the opener to be steadily and firmly held during the manipulation of the crank 32 by the other hand.

40 The diameter of the feed roller 15 is comparatively small, and is able to follow flanges of most any shaped can. It is hence well adapted for opening cans of such extremes as square and round cans.

45 The inventive ideas may receive other embodiments than that herein specifically illustrated and described.

What is claimed is:—

1. A can opener comprising a cutter and 50 a feed and pressure roller coacting with said cutter, a pair of levers on which said cutter and said feed and pressure roller are respectively mounted and by which said cutter and roller are adapted to be brought together from opposite sides of the seam of a can, a drive shaft carrying said feed and pressure roller mounted longitudinally of the lever on which said roller is mounted.

60 2. A can opener comprising a cutter and a feed and pressure roller coacting with said cutter, a pair of levers on which said cutter and said feed and pressure roller are respectively mounted and by which said cutter and roller are adapted to be brought together from opposite sides of the seam of a can, 65 a drive shaft carrying said feed and pressure roller mounted longitudinally of the lever on which said roller is mounted, and a crank for rotating said shaft at the end of said lever opposite the end at which said roller is located, said levers in closed position being adapted to be grasped in one hand and said crank turned by the other hand, and a stop

can, a drive shaft carrying said feed and pressure roller mounted longitudinally of the lever on which said roller is mounted, and means for rotating said shaft at the end of said lever opposite the end at which said roller is located. 70

3. A can opener comprising a cutter and a feed and pressure roller coacting with said cutter, a pair of levers on which said cutter and said feed and pressure roller are respectively mounted and by which said cutter and roller are adapted to be brought together from opposite sides of the seam of a can, a drive shaft carrying said feed and pressure roller mounted longitudinally of the lever on which said roller is mounted, and a crank for rotating said shaft at the end of said lever opposite the end at which said roller is located. 75

4. A can opener comprising a cutter and a feed and pressure roller coacting with said cutter, a pair of levers on which said cutter and said feed and pressure roller are respectively mounted and by which said cutter and roller are adapted to be brought together from opposite sides of the seam of a can, a drive shaft carrying said feed and pressure roller mounted longitudinally of the lever on which said roller is mounted, and a crank for rotating said shaft at the end of said lever opposite the end at which said roller is located, said levers in closed position being adapted to be grasped in one hand and said crank turned by the other hand. 90

5. A can opener comprising a cutter and a feed and pressure roller coacting with said cutter, a pair of levers on which said cutter and said feed and pressure roller are respectively mounted and by which said cutter and roller are adapted to be brought together from opposite sides of the seam of a can, a drive shaft carrying said feed and pressure roller mounted longitudinally of the lever on which said roller is mounted, and means for rotating said shaft at the end of said lever opposite the end at which said roller is located, and a stop adapted to engage said can to determine the position of said opener during the cutting operation. 105

6. A can opener comprising a cutter and a feed and pressure roller coacting with said cutter, a pair of levers on which said cutter and said feed and pressure roller are respectively mounted and by which said cutter and roller are adapted to be brought together from opposite sides of the seam of a can, a drive shaft carrying said feed and pressure roller mounted longitudinally of the lever on which said roller is mounted, and a crank for rotating said shaft at the end of said lever opposite the end at which said roller is located, said levers in closed position being adapted to be grasped in one hand and said crank turned by the other hand, and a stop 110

115

120

125

130

adapted to engage said can to determine the position of said opener during the cutting operation.

7. A can opener comprising a cutter and a feed and pressure roller coacting with said cutter, a drive shaft carrying said feed and pressure roller, said shaft being mounted longitudinally on said lever, and a guard projecting beyond the edge of said cutter 10 for protecting the cutting edge thereof.

8. A can opener comprising a stock adapted to be grasped, held and supported by hand during manipulation, a cutter, a feed and pressure roller adapted to press said 15 cutter into and through the side of a can body and to propel the opener around the can, causing the cutter to cut as it is moved with the opener, a bracket for holding said cutter, and a connection between said stock 20 and bracket comprising a rib and notch be-

tween said parts, and a pin passing through said parts.

9. A can opener comprising a stock adapted to be grasped, held, and supported by hand during manipulation, a cutter, a feed and pressure roller adapted to press said cutter into and through the side of a can body, and to propel the opener around the can, causing the cutter to cut as it is moved with the opener, said roller being mounted on a 25 lever pivoted to said stock, a bracket for holding said cutter, and a connection between said stock and bracket at two points, the connection at one point comprising a pin passing through said bracket and said 30 lever and serving as a pivot for said lever.

In witness whereof, we have hereunto signed our names.

SEWELL DAVIS.
ALPHONSE LA FON.
